P. A. BISHOP,
TENSION DEVICE,
APPLICATION FILED AUG. 8, 1921.

Patented Oct. 24, 1922.

Inventor
Peter A. Bishop

By *Elis Spear Jr.*
Attorney

UNITED STATES PATENT OFFICE.

PETER A. BISHOP, OF FALL RIVER, MASSACHUSETTS.

TENSION DEVICE.

Application filed August 8, 1921. Serial No. 490,423.

To all whom it may concern:

Be it known that I, PETER A. BISHOP, a citizen of the United States, residing at Fall River, county of Bristol, State of Massachusetts, have invented certain new and useful Improvements in Tension Devices, of which the following is a specification.

This invention relates to tension devices and particularly to tensions for yarns and threads. While my invention is in part capable of use in somewhat varied fields, I have for purposes of illustration shown as a specific embodiment, a winding machine tension as being both a satisfactory illustration of its general principles as well as a valuable and specific embodiment which I have found well adapted for practical use.

In machines of this sort, the necessity for providing tensions that will be constant over a considerable range of adjustment, have been found to be of great importance, but tensions embodying these features are somewhat difficult to secure in forms which are practically successful and commercially producible at a reasonable cost.

One of the difficulties has been to provide for adjustment to such varied tensions as may be needed for different kinds of yarns or different results and at the same time to have a tension which will run smooth and uniform for the resistance for which it is set.

Throughout specification and drawings like reference characters are employed to indicate corresponding parts and in the drawings:

Fig. 1 shows my invention embodied as a part of a spooling machine.

Fig. 2 is an elevation of the end of the bobbin frame which is broken off for the purpose of illustration, and

Fig. 3 is a plan view of the same.

In the drawings I have shown bobbin frame 1 having a clamping jaw 2 with a set screw 2' clamping it on a bobbin holder rod 3.

On the arm 1 is a bracket holder on which is a bobbin holder spindle 4 carrying the bobbin B from which the thread T is drawn. The upper end of the arm 1 which is slightly bent to overhang the bobbin B is provided with a tension device. The end of the arm 1 is provided with a transverse portion 5 and an outwardly projecting lip 6. Lip 6 is notched as at 6' to receive the thread and the lateral portion 5 is notched as at 5'. At-

tached to the end of the arm just behind the part 5 is a ball race comprising a side wall 7 which rises slightly above the main part of the race casting. This casting has a longitudinal bore 8 with an intersecting slot at its top extending from its forward end almost to its rearward end. The rearward end is notched as at 9 to make a thread guide. The race is attached to the arm 1 by a screw 10 in an ear 11, the forward end of the race resting on a shoulder 6² rearwardly projecting from the portion 5.

Within the cylindrical bore 8 are a plurality of balls 12. In the present instance a tension is shown with four balls in place, but it will be understood that tensions may be made with greater or less number of balls and the number of balls in any given race may be diminished from its maximum number by removing one or more balls when it is desired to reduce the tension.

I provide a takeup 13 adjustably mounted as at 14 upon the upper inner edge of the ball race. As here shown, the takeup 13 is in the form of a plate which is slidably mounted upon the race casting and is provided with a longitudinally extending slot 13² in which is disposed the set screw 14 for holding the adjustment of said takeup. The takeup 13 has a follower 13' which extends down into the bore 8 of the race casting so as to support the lowest ball of the race. Just below the tension I also provide a guiding stud or knob 15 about which the thread may be passed to keep it in proper position below the balls in the race. By loosening the set screw 14 and sliding the follower 13 axially relative to the raceway of the race casting, the position of the balls 12 relative to each other will be changed and the tension on the thread varied.

The thread is led from the bobbin B up through the notch 6' and into the guide through the notch 5' and being drawn down beneath the balls 12 which have enough play to permit the thread to be drawn through the bottom of the cylindrical bore 8 and under the central vertical axis of each.

The thread also passes the end of the follower 13' and the notch or opening 9 at the rear of the follower. At this point it is turned about the knob 15 from which it passes to a spool which is not shown.

The action of the balls 12 on the thread T produces a uniform, steady tension and

one which at the same time is very free running. Adjustment may be made quickly and with considerable certainty as there is no such variation in the increase and diminution of the tension as occurs in the case of ordinary spring tensions or friction tensions.

My tension device is capable of being made in a great variety of sizes either by varying the length of the cylindrical race or by varying the diameter of the balls.

While I have referred to my friction elements as balls it will be understood that this is illustrative and that any other roller or rotative element may be employed. The ball and cylindrical bore construction has considerable commercial advantage as the balls are procurable as standard articles of manufacture in a highly developed state both as to uniformity in weight and curvature, and in smoothness and hardness of finish.

The rotating elements are not only removable and replaceable for purposes of varying tension but obviously may be replaced without much trouble or expense, if worn or rusted.

My invention is capable of a variety of modifications and embodiments and may be variously applied and used all without departing from the spirit of my invention if within the limits of the appended claims.

What I therefore claim and desire to secure by Letters Patent is:

35 1. In tension device of the class described comprising a thread guide, a raceway included in said guide, removable and replaceable rotative friction elements in said raceway and a follower mounted for axial adjustment with reference to said raceway and adapted to contact the rear side of the last ball therein.

40 2. In tension device of the class described comprising a thread guide, a raceway included in said guide, removable and replaceable spherical friction elements in said raceway and a follower mounted for axial adjustment with reference to said raceway and

adapted to contact the rear side of the last ball therein.

50 3. In tension device of the class described comprising a thread guide, a cylindrical raceway included in said guide, removable and replaceable spherical friction elements in said raceway and a follower mounted for axial adjustment with reference to said raceway and adapted to contact the rear side of the last ball therein.

55 4. In a winding machine of the class described, a bobbin frame having a thread guide at its end and a thread tension device set behind said thread guide and comprising a block having a cylindrical bore with an intersecting slot at its top, an axially adjustable follower mounted on said block and disposed through said slot and a plurality of the balls in said bore and loosely fitting therein and supported in axial alignment therewith by said follower.

60 5. In a winding machine of the class described, a bobbin frame having a thread guide at its end and a thread tension device having a cylindrical bore with a plurality of the balls in said bore and loosely fitting therein and a follower adjustable axially 65 of said bore and contacting the end ball therein.

65 70 75 6. In a winding machine of the class described, a bobbin frame having a notch thread guide at its end and a thread tension device set behind said thread guide and supported thereby and comprising a block having a cylindrical bore with an intersecting slot at its top, an axially adjustable follower mounted on said block and having a ball contacting portion disposed through said slot and a plurality of the balls in said bore and loosely fitting therein and supported in axial alignment therewith by said ball contacting portion of the follower.

75 80 85 90 In testimony whereof I affix my signature in presence of two witnesses.

PETER A. BISHOP.
